UNITED STATES PATENT OFFICE.

GEORGE P. OHLGART, OF BALTIMORE, MARYLAND.

IMPACT DETONATOR FOR SHELLS OR PROJECTILES.

1,411,889.

Specification of Letters Patent. Patented Apr. 4, 1922.

Application filed February 28, 1920. Serial No. 362,033.

To all whom it may concern:

Be it known that I, GEORGE P. OHLGART, a citizen of the United States, residing at Baltimore, in the State of Maryland, have 5 invented certain new and useful Improvements in Impact Detonators for Shells or Projectiles, of which the following is a specification.

This invention relates to improvements in 10 impact detonators for shells or projectiles.

The objects of the invention are to provide an improved detonator whose firing device will be normally locked in a safety position: whose locking means will be moved to the 15 release position only by centrifugal force created by rotation of the shell or projectile in flight and will become locked in the release position until impact.

A further object of the invention is to provide 20 an improved means for returning the detonator parts to a safety condition in case the shell or projectile fails to explode on impact.

With these, and other objects in view, the 25 invention is illustrated in the accompanying drawing, wherein,—

Fig. 1 shows a longitudinal section through a fuse-body or stock with the improved detonator shown in side elevation therein.

30 Fig. 2 illustrates the detached detonator in top plan.

Fig. 3 shows the same in longitudinal section to illustrate the parts in the safety position,—the section being taken on the line 35 3—3 of Fig. 2.

Fig. 4 illustrates the same but with the locking bolts held retracted to leave the parts free to operate upon impact.

Fig. 5 shows another view of the same 40 parts, the latter however being illustrated in the firing position which they assume at the moment of impact, and

Fig. 6 illustrates another longitudinal section 45 through the detonator,—the section being taken on the line 6—6 of Fig. 2.

Referring to the drawing by numerals, 7, 50 designates a fuse body or stock of conventional construction, having the usual exterior screw-threads 8, and an interior chamber 9. A plug 10, closes the inner end of the chamber 9, and this plug carries a primer cap 11, the flash from which may pass through the passages 12, to a booster or main charge in the shell or projectile.

55 A detonator body 13, is located in the chamber 9, of the stock and completely fills

the latter so that no possible longitudinal movement of the detonator body can take place in said chamber. It is therefore to be understood that in no sense is the detonator 60 body a plunger, or the equivalent of a plunger, because it has no movement independent of the stock and preferably is sufficiently tight in the chamber to prevent independent rotation in said chamber.

65 The detonator body 13, has a chamber 14, at what may be termed its outer end, and is provided with a central passage 15, which extends from said chamber 14, and opens at the inner end of the body. By preference I 70 provide an annular groove or channel 16, around the inner end of the detonator chamber 14, for a purpose that will presently be explained.

75 The inner end of the detonator body is provided with cross-wise or radial passages 17, in that said passages extend laterally from the central passage 15. In practice I find that two such passages 17, are sufficient, but it is obvious that a greater number of 80 passages may be employed. Preferably, the passages 17, are located at diametrically opposite sides of the central passage, and extend from the central passage toward the circumference. Each passage 17, contains a 85 locking bolt 18, and each bolt has an enlarged inner end and a reduced outer end 19. The reduced end of each bolt is encircled by a coiled spring 20, which latter is confined in the passage, in this instance by means of a 90 circular band 21, that extends entirely around the inner end of the detonator body. It is therefore to be understood that the springs 20, are normally under sufficient compression to press the bolts 18, toward the 95 central passage 15, but will yield when the body is rotated and permit the bolts to be thrown radially and away from the central passage by the centrifugal force set up by the rotation of the shell in flight.

100 On the interior of the detonator body I provide a firing-pin structure which comprises a circular head 22, that loosely fits the chamber 14, and which has a central post 23, that projects into the central passage 15. 105 The post carries a pin 24, which extends into the central passage and normally has position between the inner ends of the bolts, as clearly shown in Figs. 2 and 3 of the drawing.

110 A shoulder 25, is formed on the post 23, around the base of the firing pin and when

the firing pin structure is in the normal safety position, this shoulder 25, is engaged by the enlarged ends of the locking bolts 18,—the bolts in this instance projecting 5 over the shoulder at diametrically opposite sides of the firing pin, so as to hold the entire firing-pin structure against forward movement in the detonator body.

By reference to Fig. 3, it will be seen that 10 when the shoulder 25, is engaged by the locking bolts, the pin 24, will be held within the central passage 15.

A spiral spring 26, is located in the detonator chamber 14, and has one end seated 15 in the annular groove 16, and its other end encircling the post 23, and seated against the head 22, so as to yieldingly press the head in a direction away from the bolts and toward the outer end of the detonator 20 chamber.

A disk 27, is secured in the outer end of the detonator to form a stop for the firing device while the latter is in its normal position.

25 One of the objects of this invention is to provide means for retaining the locking bolts in a retracted position after they have become retracted through centrifugal force caused by rotation of the shell in flight. 30 The advantage in this is that should the speed of rotation be materially reduced after the shell has been fired and before it strikes, there is a liability of the locking bolts returning to their normally locked 35 positions, and should this occur, when impact takes place the firing mechanism cannot move forward to strike the primer and failure of the shell to explode would be the result. To meet this possible condition I 40 provide means to engage the locking bolts and hold them spread apart which will now be described.

By reference to Figs. 2—3—4 and 6 of the drawings, it will be noted that the inner 45 end of the detonator body is provided with two slots 28, which are parallel and extend, in this instance, in a direction at right angles to the passages 17, in which the locking bolts are confined. These slots are 50 spaced and have positions at opposite sides of the central passage 15. Each slot contains a spring finger 29, the free yielding end of which normally lies on top of the enlarged end of the bolt, as shown in Figs. 55 3 and 6 of the drawing.

Beneath each spring finger 29, I provide a loose plunger 30, which has a reduced end 60 that projects into the detonator chamber 14, so that when the head 22, of the firing device moves forward it may strike said reduced end and thereby move the plungers 30, forward, for a purpose presently to be explained.

In Figs. 2 and 3 the normal safety position of the locking bolts and the spring

fingers 29, are shown. In this safety position the fingers simply rest upon the enlarged ends of the locking bolts. When the locking bolts are thrown back by centrifugal force to the positions shown in Fig. 4, 70 the spring fingers move down into the slots in front of the ends of the bolts and bar the return movement of those bolts even though rotation of the shell is completely stopped.

It will thus be seen that after the bolts are retracted, they are locked in the retracted position by the spring fingers and the firing device will be free to plunge forward 75 immediately upon the shell striking an object. This forward movement of the firing devices is illustrated in Fig. 5, of the drawing. By comparing this Fig. 5, which shows the parts in firing position, with Fig. 4, 80 which shows the same parts as armed but not yet having moved forward, it will be seen that not only has the firing pin structure moved forward, but the locking bolts 18, have been released by the spring fingers 29, which latter, at the moment firing should 85 take place, have moved from in front of the bolts: the bolts have moved forward against opposite sides of the post 23, and the spring fingers then press on the forward circumferential ends of the bolts. This 90 change in the parts is due to the fact that when the firing-pin structure moves forward the head 22, will strike the reduced ends of the plungers 30, thereby pushing 95 those plungers forward. As the plungers 100 move forward they engage the under sides of the spring fingers 29, and lift the latter from in front of the locking bolts. The locking bolts then move toward and seat against the diametrically opposite sides of the post 23, so that if a failure to explode 105 occurs the firing-pin structure will be moved back by spring 26, and the locking bolts will spring over the shoulder 25, on the post and again lock the firing-pin structure in 110 the safety position.

From the foregoing explanations it will be seen that the structure is so arranged as to normally lock the firing pin in a safety position, then when the shell is fired will 115 retract the bolts and lock those bolts in a retracted position and finally in case of failure to explode, the bolts are released and the pin returns to normal position where the bolts again lock it in safety.

Having described my invention, what I claim is,—

1. The combination with a fuse stock having a chamber, of an explosive element at one end of said chamber, a detonator body 125 completely filling the chamber and having a chamber with a central passage and a plurality of lateral passages which open into the central passage, a firing device in the detonator chamber and having a post that 130

extends into the central passage, a locking bolt in each lateral passage to engage and hold the post from movement in the central passage, a spring to normally press each 5 bolt toward the central passage and a band around the detonator body and closing the outer ends of the lateral passages.

2. The combination with a fuse stock having a chamber, of an explosive element at 10 one end of said chamber; a detonator body filling said chamber and held against longitudinal movement in the latter said detonator body also having a chamber therein and further provided with a central passage 15 and a plurality of lateral passages opening into the central passage; a firing device having an enlarged head in the detonator chamber, a post extending from the head into the central passage and a pin projecting 20 from the post and normally having position between the inner ends of the lateral passages; a locking bolt in each lateral passage to hold the firing device against forward movement and yielding means in the 25 detonator chamber to normally press the enlarged head of the firing device in a direction away from the explosive element.

3. The combination with a fuse stock having a chamber, of an explosive element at 30 one end of said chamber; a detonator body filling said chamber and held against longitudinal movement in the latter said detonator body also having a chamber therein and further provided with a central passage 35 and a plurality of lateral passages opening into the central passage; a firing device having an enlarged head in the detonator chamber, a post extending from the head into the central passage and a pin projecting 40 from the post and normally having position between the inner ends of the lateral passages; a locking bolt in each lateral passage to hold the firing device against forward movement and means for engaging the 45 locking bolts after they have moved laterally to release the firing device to hold said bolts in the release position.

4. In a firing device for projectiles the combination with a movable firing pin, of 50 means for normally holding the firing pin

against movement said means being operated by centrifugal force during rotation of the projectile in flight; means for locking the said holding means in the centrifugally-operated position before the projectile 55 strikes and means for releasing said locking means when the firing pin is moved to the firing position.

5. In a firing device for projectiles the combination with a movable firing pin, of 60 means for normally holding the firing pin against movement said means being operated by centrifugal force during rotation of the projectile in flight; means for locking the said holding means in the centrifugally- 65 operated position before the projectile strikes and means actuated by the firing pin to move the locking means and allow the holding means to return and again lock the firing pin in a safety position upon failure 70 of the projectile to explode.

6. In a firing device for projectiles the combination with a movable firing pin, of means for normally holding the firing pin against movement said means being operated by centrifugal force during rotation of the projectile in flight; means for locking the said holding means in the centrifugally-operated position before the projectile 75 strikes; means for returning the firing pin 80 to the normal position upon failure of the explosion and means for restoring the holding means to again lock the firing pin in the safety condition.

7. In a firing device for projectiles the combination with a movable firing pin, of 85 means for normally holding the firing pin against movement said means being operated by centrifugal force during rotation of the projectile in flight; means for locking 90 the said holding means in the centrifugally-operated position before the projectile strikes; spring means for returning the firing pin to the normal position upon failure 95 of explosion and to restore the locking and holding means to the normal position to again lock the firing pin in a safety condition.

In testimony whereof I affix my signature.
GEORGE P. OHLGART.
